VELOCIPEDE

Allan L. McGregor, Chicago, Ill.

Application September 11, 1936, Serial No. 100,292

4 Claims. (Cl. 280—250)

This invention pertains to velocipedes, and more particularly to velocipedes of the type that are steered by the feet and propelled by the arms and hands of the rider. In its preferred form 5 herein disclosed the vehicle is a quadricycle with a pair of steering wheels in front and a pair of wheels at the rear either or both of which have the character of a traction wheel.

Among the objects of the invention have been, 10 to provide a velocipede for children's use of exceptionally strong, rugged and durable construction, to provide a velocipede having a broad wheel base and low center of gravity practically incapable of overturning in use, and hence safe for 15 very young children, to provide a novel and unique propulsion mechanism adapted to afford a novel exercise of the arm, shoulder, chest and back muscles of the rider, and one that avoids dead centers, to provide a manually propelled vehicle 20 that will constitute a useful exercising machine as well as a carrier, and to provide a vehicle that, by reason of its partial resemblance to the modern stream-lined automobile, will appeal to the imagination of children.

Still other objects and attendant advantages 25 of the invention will be apparent to persons familiar with vehicles of this type from the following detailed description, taken in connection with the accompanying drawings in which I have illustrated one approved embodiment of the invention, and wherein—

Fig. 1 is a top plan view, with the rear portion of the seat broken off to disclose underlying parts.

Fig. 2 is a side elevation partly in longitudinal 30 vertical section.

Fig. 3 is a vertical transverse section on the line 3—3 of Fig. 2.

Fig. 4 is a vertical transverse section on the line 4—4 of Fig. 1.

Fig. 5 is a fragmentary vertical transverse section on the line 5—5 of Fig. 2.

The body frame or chassis, including the seat, is constructed substantially as follows. 10 designates a central straight longitudinal bar, which 45 may be of wood, and 11 designates each of a pair of symmetrical side bars consisting of metal strips bent to substantially the form shown in Fig. 1 and at their front and rear ends secured to the sides of the front and rear portions of the bar 10.

Attached to the under side of the front end of the central bar 10 is an upwardly and rearwardly extending metal strip 12, and attached to the upper side of the rear end of the bar 10 is an upwardly and forwardly extending metal strip 13.

65 A vertical strut 14 (Fig. 2) rigidly connects and

spaces the upper horizontal portion of the strip 12 and the central bar 10. Resting upon and bolted to the upper horizontal portions of the strips 12 and 13 is the wooden seat 15, the side edges of which slightly overlap the widened intermediate portions of the side bars 11 as shown in Fig. 1. An inverted U-shaped vertical strut 16 rigidly connects and spaces the seat 15 and the side bars 11. To and crosswise of the under side of the forward portion of the seat board 15 is 10 attached a flat metal strip 17 serving as a cleat to forestall any possible splitting of the board.

The running gear, which supports the body frame or chassis above described, preferably consists of the following. 18 designates the front 15 axle which consists of a straight rod, and 19 are the front or steering wheels journaled on the ends of the axle 18. Suspended from the axle shaft 18 is a yoke comprising a flat horizontal intermediate portion 20 and a pair of upstanding 20 arms 21 that are pivoted on the axle 18. As best shown in Fig. 5, the forward portion of the main longitudinal bar 10 rests on and crosswise of the yoke member 20 and is connected thereto by a king bolt 22. I have also shown a foot guard 25 mounted on and crosswise of the bar 10 and connected thereto by the king bolt 22, this guard also being in the general form of a yoke and comprising a horizontal portion 23 and apertured upstanding arms 24 through which the axle 18 30 extends. For steering the device, the driver rests his feet on the portions of the axle between the yoke arms 21 and the opposite sides of the chassis frame, and the arms 24 of this foot guard prevent the feet interfering with the free swiveling movements of the front axle. This foot guard is, of course, not necessary, and may be omitted if desired. To the arms 21 are attached the rear ends of a forwardly projecting bumper bar 25. 26 designates the rear axle on the ends of which are 40 the rear wheels 27 and 27'. As best shown in Fig. 3, the wheel 27 is a traction wheel and is secured fast on the axle by means of an inner hub 28 that is pinned to the axle; while the companion wheel 27' is journaled on the other end 45 of the axle, this mounting of the rear wheels providing for the usual differential movement of the wheels when traveling a curved path.

Suspended from the rear axle 26 are a pair of hangers 29, the widened lower ends of which are 50 attached to the side frame bars 11 as by bolts 30. These bolts preferably extend through longitudinal slots 31 in the frame bars 11 so that the hangers 29 can be adjusted, when required, to take up slack in the driving belt hereinafter de- 55

scribed. In the hubs of the hangers 29 are oil holes 32 (Fig. 1).

Encircling the axle 26 between the hub of the wheel 27' and the adjacent hanger 29 is a coil thrust spring 33 that forms an elastic spacer between the hub of the adjacent hanger 29 and the inner end of the hub of wheel 27'. A rear bumper 34 has its side arms attached to the outer sides of the frame bars 11 by the same bolts 30 which attach the hangers 29 to said frame bars. The rear wheels 27, 27' are preferably equipped with wheel guards 35 that are supported at their forward ends by brackets 36 (Figs. 1 and 2) attached to the vertical limbs of the strut 16, and at their top portions by a bent cross bar 37 (Figs. 1 and 3) that is attached centrally to the under side of the rear portion of the seat 15, by a bolt 38 and at its ends is attached to the under sides of the guards 35. A central depending tail piece 39 overlies and conceals the rear frame strip 13, being secured to the latter by screws 40, its upper end portion extending a short distance beneath the rear end of the seat board 15.

Describing next the propelling mechanism, 41 designates a post or pedestal having an elongated base 42 resting upon and attached by bolts 43 to the main longitudinal bar 10. The upper portion of the post 41 is transversely apertured to form a bearing for a horizontal shaft 44, on one end of which is pinned the hub of a bevel gear 45, and on the opposite end of which is pinned a grooved pulley 46. The top of the post 41 is recessed as shown at 48 in Fig. 4 to receive the lower end of a vertical drive shaft 47 that extends upwardly through a hole in the forward frame strip 12, a registering hole in the seat board 15, and a bearing block 48 mounted on the top of the seat board. The lower portion of the shaft 47 also extends through the intersecting horizontal portions of two brackets 49 and 50 disposed at right angles to each other, the bracket 49 being mounted on the central bar 10 and the bracket 50 being attached at its lower end to one of the side frame strips 11 (Fig. 4). Secured to the top limb of the bracket 49 is a bearing block 51 for the shaft 47. Pinned to the lower portion of shaft 47 beneath the bracket 50 is the hub of a bevel gear 52 that meshes with and drives the bevel gear 45. Fast on the rear axle 26 is a grooved pulley 53 that is connected by a V-belt 54 with the pulley 46. Pinned to or otherwise secured to the upper end of the shaft 47 is a shaft extension 55, fast on the upper end of which is a crank arm 56. On the free end of the crank arm 56 is an upstanding pin 57 on which is centrally pivoted a handle bar 58 preferably of the ram's horn shape shown in Fig. 1, and swiveled on the two ends of the handle bar 58 are the handle pieces 59.

60 To conceal the forward portion of the propelling mechanism, I preferably employ a V-shaped shield or guard, the apex 60 of which is attached to the vertical strut 14, while the two side wings 61 are attached to vertical brackets 62 upstanding from the side bars 11. This device not only conceals a portion of the propelling mechanism, but it also functions as a stream-lined prow to split the wind and also as a guard to prevent the trouser legs or skirt of the rider from being caught in the gears. This front shield or guard, together with the rear wheel guards 35, the front

and rear bumpers 25 and 34 and the depending tail guard 39 to a certain extent simulate corresponding features of the modern high speed automobile, and to that extent appeal to the imagination of children who are quite as keen to be 5 modern and up to date in their riding equipment as their elders.

The mode of propelling the device is doubtless obvious from the foregoing description of its structural features. The child seats himself on 10 the seat board 15 with his feet on the axle 18 (or, if his legs are too long, on the bumper bar 25), grasps the handles 58, and rotates the latter bodily in a circular clockwise direction viewing Fig. 1 around the axis of the drive shaft. This, 15 through the bevel gear and belt and pulley transmission described, imparts a forward drive to the vehicle. The continuous circular movement of the operating handle calls forth a novel, unique and unusual exercise of the arm, shoulder and 20 chest muscles, so that the device constitutes a useful exercising machine as well as a toy vehicle; and a distinct advantage of the propulsion mechanism lies in the fact that it obviously avoids dead centers.

Obviously, minor changes in the structural details of the device may be resorted to within the spirit and purview of the appended claims.

I claim:

1. In a velocipede of the type described, the 30 combination with a chassis frame, front and rear supporting wheels, a rear axle journaled in said frame fast with at least one of the rear wheels, and a driver's seat mounted on said frame, of a vertical shaft journaled in a bearing on said 35 frame, transmission mechanism from said shaft to said rear axle, a horizontal crank arm fast on the upper end of said shaft, and a handle bar pivoted on said crank arm.

2. In a velocipede of the type described, the 40 combination with a chassis frame, front and rear supporting wheels, a rear axle journaled in said frame fast with at least one of the rear wheels, and a driver's seat mounted on said frame, of a vertical shaft journaled in a bearing on said 45 frame and extending through the front portion of said seat, a bearing on said seat for said shaft, transmission mechanism from said shaft to said rear axle, a crank arm fast on the upper end of said shaft, a horizontal handle bar centrally pivoted on the free end of said crank arm, and upstanding handles on the ends of said handle bar.

3. Propulsion mechanism for a velocipede having a rear axle and traction wheels on the ends of said axle, comprising a horizontal handle bar 55 having vertical handles on its ends adapted to be grasped by the rider and bodily movable in a circular path in a horizontal plane, and dead-centerless transmission mechanism actuated by said handle bar extending from the longitudinal center of the latter to said rear axle.

4. Propulsion mechanism for a velocipede having a rear axle and traction wheels on the ends of said axle, comprising a rotatable vertical shaft having a crank arm on its upper end, a horizontal handle bar pivoted at its longitudinal center on the free end of said crank arm, vertical handles on the ends of said handle bar, and transmission mechanism extending from said vertical shaft to said rear axle.

ALLAN L. McGREGOR.
